UNITED STATES PATENT OFFICE.

CHARLOTTE J. TAYLOR, OF BRIDGETON, INDIANA.

DESIGN FOR A SUPPORT FOR CHRISTMAS-TREES.

SPECIFICATION forming part of Design No. 29,801, dated December 13, 1898.

Application filed November 7, 1898. Serial No. 695,793. Term of patent 14 years.

To all whom it may concern:

Be it known that I, CHARLOTTE J. TAYLOR, a citizen of the United States, residing at Bridgeton, in the county of Parke and State of Indiana, have invented and produced a new and original Design for a Support for a Christmas-Tree or Similar Article, of which the following is a specification, reference being had to the accompanying drawings, forming a part thereof, and in which—

As shown in the drawings, the leading or material feature of my design consists of a pedestal or support made up of a plurality of sections, the adjacent or meeting edges of which are beveled and which unitedly form a triangular opening in the socket portion, and radiating legs or supports leading from the lower end thereof. Along the upper edge of each side of the triangular socket-piece beading is arranged, and along the outer surface of the support, adjacent to the meeting edges or corners of the sections thereof, is arranged open fret or scroll work of the design illustrated. Similar scroll or fret work is arranged adjacent to the lower edges of the sides. Around the sides of the socket-piece are ornamental shelves or brackets.

Having now described the invention, what is claimed is—

The design for a support for a Christmas-tree or similar article, substantially as shown and described.

In testimony whereof I affix my signature in presence of two witnesses.

CHARLOTTE J. TAYLOR.
